CLAIM

The ornamental design for an over the counter medicinal container with surface ornamentation, as shown and described.

DESCRIPTION

FIG. 1 is a perspective view of an over the counter medicinal container with surface ornamentation;

FIG. 2 is a front view thereof;

FIG. 3 is a left side view thereof;

FIG. 4 is a back view thereof;

FIG. 5 is a right side view thereof;

FIG. 6 is a top view thereof; and,

FIG. 7 is a bottom view thereof.

The evenly broken lines are shown for the purpose of illustrating parts of the article that form no part of the claim. The dot-dash lines represent the boundaries of the claim and form no part thereof.

1 Claim, 3 Drawing Sheets
